CLAIM

I claim the ornamental design for a sports board with integrated motor compartment, as shown and described.

DESCRIPTION

FIG. 1 is an assembled drawing of the sports board with integrated motor compartment showing my new design;

FIG. 2 is a back view thereof;

FIG. 3 is a front view thereof;

FIG. 4 is a right side view thereof;

FIG. 5 is a left-facing view thereof;

FIG. 6 is a top view thereof.

FIG. 7 is a bottom view thereof; and,

FIG. 8 is a top view showing the integrated motor compartment door removed.

The broken lines in the drawing are for illustrative purposes only and form no part of the claimed design.
